LAZY-TONGS EXPANSIBLE LINK CHAIN FOR
A BRACELET OR THE LIKEJoseph M. Bender, Manhasset, N. Y., assignor to
Jacoby-Bender, Inc., New York, N. Y., a corpo-
ration of New York

Application November 16, 1948, Serial No. 149,663

Term of patent 7 years

(Cl. D45—16)

To all whom it may concern:

Be it known, that I, Joseph M. Bender, a citizen of the United States and a resident of Manhasset, county of Nassau, and State of New York, have invented a new, original, and ornamental Design for a Lazy-Tongs Expansible Link Chain for a Bracelet or the like, of which the following is a specification, reference being had to the accompanying drawing forming a part thereof, in which:

Fig. 1 is a top plan view of a lazy-tongs expansible link chain showing my new design;

Fig. 2 is a similar view of a fragment of the chain in an expanded position, the conventional bottom links being visible between the expanded top links;

Fig. 3 is an end view of one of the top links of the chain; and

Fig. 4 is a side view of one of the top links of the chain taken from the right hand side of Fig. 1.

I claim:

The ornamental design for a lazy-tongs expansible link chain for a bracelet or the like, as shown.

JOSEPH M. BENDER.
